United States Patent Office.

GEORGE D. STEVENS, OF NEW YORK, N. Y.

Design No. 4,562, dated January 3, 1871.

DESIGN FOR A CHAIN-HOOK.

The Schedule referred to in these Letters Patent and making part of the same.

To all whom it may concern:

Be it known that I, GEORGE D. STEVENS, of the city, county, and State of New York, have invented a new and original Design for Chain-Hook; and I do hereby declare the following to be a full, clear, and exact description, which will enable those skilled in the art to make and use the same, reference being had to the accompanying drawing forming part of this specification, which drawing is a front view of this design.

My invention relates to a chain or snap-hook, the front or body of which is made in the form of a horseshoe, whereby it obtains a new, elegant and distinguishing appearance.

In the drawing—

The letter A designates a snap-hook, the front or body, a, of which is made in the form of a horseshoe, as shown.

What I claim as new, and desire to secure by Letters Patent, is—

The design for a chain or snap-hook, as herein shown and described.

GEO. D. STEVENS.
